UNITED STATES PATENT OFFICE.

JOSEPH A. BLACK, OF CHARLESTON, SOUTH CAROLINA.

STREET-SIGN.

1,287,196.

Specification of Letters Patent. Patented Dec. 10, 1918.

Application filed July 8, 1918. Serial No. 243,765.

To all whom it may concern:

Be it known that I, JOSEPH A. BLACK, a citizen of the United States, residing at Charleston, in the county of Charleston, State of South Carolina, have invented certain new and useful Improvements in Street-Signs, of which the following is a description, reference being had to the accompanying drawings, forming a part hereof.

10 My invention relates to street signaling devices and has for its object to provide a simple inexpensive readily portable device which can be placed wherever desired to warn drivers of vehicles or others of obstruction or necessity for changing speed, avoiding unnecessary noise or other cautionary or other warning necessary to be given.

15 A further object of the invention is to provide a device of this character which will carry a plurality of cautionary or other signs, any one of which may be displayed, the displayed sign being locked in displayed position and all the others so locked that they cannot be displayed.

20 25 A further object of the invention is to provide a device of this character which will be adapted to carry a lantern for night use and in which the lantern so used will be locked against removal.

30 35 A further object of the invention is to provide a device of this character which may be constructed of materials in common use without the use of special tools.

With these and other objects hereinafter explained the invention consists in the construction and combination of elements hereinafter set forth and claimed.

Referring to the drawings:

Figure 1 is a side elevation of a street 40 signaling device embodying my invention.

Fig. 2 is a front elevation of the same.

Fig. 3 is a vertical sectional view of the casing containing the signs on an enlarged scale.

45 Fig. 4 is a front view of the portion of the device shown in Fig. 3, and

Fig. 5 is a horizontal sectional view on line 5—5 of Fig. 4.

In the drawings 1 indicates a casing open 50 at one side in which a series of indicating signs 2 are pivoted and so arranged that any one of them may be swung outward and downward so as to be visible, the one thus exhibited being arranged to be locked in

exhibited position and the others to be 55 locked against being swung downward into visible position.

The casing 1 is arranged to be supported on a standard 3 carried by a base 4. A vertical arm 5 extends upward from the 60 top of standard 3 along the rear of the casing 1 which is secured to it, and has at its upper end a horizontal arm 6 extending over the top of the casing and forked at its end to receive the bail of a lantern the base of 65 which rests in a flanged plate 7 carried on the top of the casing. The forked ends 8 of arm 6 are perforated at 9 to receive the bow of a padlock 10 by which the bail of the lantern is locked against removal. 70

The series of indicating signs 2 are pivoted in the lower part of the casing on a rod 11, this rod and the holes in the indicating signs through which it passes being so located than when the signs are dropped 75 to exhibiting position the inner portions of their lower and front edges will strike and rest on a suitable abutment 12 near the front edge of the casing so as to extend outward in horizontal position. 80

Through the side walls of the casing near the front edges of these walls extends a removable locking belt 13. The holes in the side walls of the casing through which this locking bolt passes are located a distance 85 above the abutment 12 slightly less than the width of the indicating signs and at such distance from the pivot rod 11 that when in place the locking bolt will be in front of all of the indicating signs which are in vertical position within the casing and will pass through a recess 14 found in the upper edge of the indicating sign which has been swung downward into exhibiting position, the locking bolt thus serving to hold the sign which is in exhibiting position against being swung upward to return it to the casing and at the same time to hold the other signs from being swung down out of the casing. The locking bolt is provided with a suitable head 15 at one end and at the other end is provided with a hole 16 through which the bow of a padlock 17 may be inserted. 95

Near the upper front edge of its side walls the casing is preferably provided with a swinging bail 18 pivoted on stub bolts 19 which may be swung over the upper front ends of the indicating signs to hold them 100 105

temporarily against swinging forward and downward and may be swung upward to release the signs.

The indicating signs are preferably arranged between plates 20 by which the signs are kept from contact with each other, these plates extending upward from the lower end of the casing a distance only slightly greater than the width of the signs and the first and last of the series of signs are preferably kept from contact with the side walls of the casing by plates 21 preferably of wood. The plates 20 and 21 extend above the level of the locking bolt 13 and are perforated to receive this locking bolt, the locking bolt being thus sustained at numerous points throughout its length so that it cannot be bent.

The flange of the flanged plate 7 is of such height and the distance from the flanged plate to the horizontal arm 6 is such that when the base of the lantern is in the fork of the horizontal arm the lantern cannot be lifted out of the flanged plate.

The standard 3 is preferably formed of ordinary water or gas pipe with an ordinary T 22 coupling at its upper end into one end of which is inserted a nipple 23 and into the other end of which is inserted an elbow 24 into the upturned end of which is secured by means of an ordinary reducer, a piece of relatively small pipe forming the vertical arm 5. An elbow 25 at the upper end of arm 5 carries the horizontal arm 6. The casing 1 is supported on a shelf 26 carried on the T 22 and is suitably secured at its back to the vertical arm 5. The supporting frame work may thus be readily formed from ordinary water or gas pipe and fittings thus making a strong but inexpensive supporting frame which can readily be constructed in any steam or gas fitting shop. The casing 1 is preferably formed of sheet metal bent to the shape of a box open on one side. The indicating signs are preferably of sheet metal and may be of any desired number each sign being painted and lettered to give the information desired.

It will readily be seen that when the appropriate sign intended to be displayed has been swung down into place and the locking bolt 13 placed in position and locked by its padlock, the sign cannot be changed without unlocking the padlock. And for night use when the lantern, usually a red lantern is placed in position and its bail locked in

the fork of arm 6, it cannot be removed or tampered with except by some one having the key of the padlock.

A casing 1 of convenient size will carry twelve or more signs each of course lettered to indicate the character of obstruction or directions to drivers of vehicles or others. By the use of a dozen signs practically all of the warnings or directions likely to be needed can be provided for. When all of the signs are swung upward into the casing and locked by the locking bolt the complete device may be readily transported to the place where it is needed and when placed in position the appropriate sign may be swung down into exhibiting position and there locked and the device can then be safely left without risk of being interfered with.

Having thus described my invention what I claim is:

1. A street sign exhibiting device comprising a series of signs pivoted near their lower ends on a common pivot, a casing inclosing the signs open at its front and locking means carried by the casing adapted to lock a sign in exhibiting position and to lock other signs within the casing.

2. A street sign exhibiting device comprising a series of signs pivoted near their lower ends on a common pivot, a casing inclosing the signs open at its front and locking means carried by the casing adapted to lock a sign in exhibiting position and to lock other signs within the casing consisting of a locking bolt extending through the side walls of the casing at a point above and in front of the pivot.

3. A street sign exhibiting device comprising a series of signs pivoted near their lower ends on a common pivot, a casing inclosing the signs open at its front, means on the upper end of the casing for supporting a lantern, an arm extending over the upper end of the casing adapted to receive and retain the bail of the lantern.

4. A street sign exhibiting device comprising a series of signs pivoted near their lower ends on a common pivot, a casing inclosing the signs open at its front, means on the upper end of the casing for supporting a lantern, comprising a flanged plate and an arm extending over the flanged plate having its end forked to receive the bail of the lantern.

In testimony whereof I affix my signature this 22 day of June, 1918.

JOSEPH A. BLACK.
